UNITED STATES PATENT OFFICE

2,555,472

VENTILATOR

James F. Lilly, Portland, Oreg.

Application September 14, 1946, Serial No. 697,100

1 Claim. (Cl. 98—88)

1

This invention relates to improvements in ventilators for dwellings, buildings, and structures of all kinds wherein it is desirable or necessary to provide controlled ventilation or the passage of air therethrough.

One of the principal objects of the invention is the provision of a ventilator which is of simple, efficient, durable, and inexpensive construction, which may be conveniently installed with a minimum amount of labor through the well of a building and preferably below a sill of a window.

A further object is the provision of a balanced closure means which may be adjusted into a variety of positions for regulating the passage of air through the ventilator.

A still further object is the provision of a novel method of weather stripping throughout the operative range of said closure means.

These and other objects will appear as my invention is more fully hereinafter described in the following specification, illustrated in the accompanying drawing and finally pointed out in the appended claim.

In the drawing:

Figure 1 is a front elevation of a ventilator made in accordance with my invention and with a fragment broken away for convenience of illustration.

Figure 2 is a sectional view taken approximately along the line 2—2 of Figure 1.

Referring now more particularly to the drawing.

Reference numeral 1 indicates generally a frame having side walls 2 and 3, top and bottom walls 4, and 5, respectively, and a partial front wall 5A. The top wall 4 may constitute an entire window sill or a section thereof, and so designed or shaped to match the remaining sections or portions thereof. The ventilator in its entirety is installed beneath a window by forming an opening through the wall of the same size as that of the frame. The opening and frame may extend entirely to the floor or to any desired depth below the window. As shown in Figure 1, the invention is viewed from the exterior of the wall to which it is applied. To the side walls 2 and 3 of the frame, I secure a plurality of outwardly louvres 6 in fixed spaced relation to each other as shown. To the interior of the frame and directly behind the louvres, I mount a screen 7 by means of a frame 8. Spaced apart from the screen and also secured to the interior of the frame 1, is a frame 9 made of weather-stripping material of channel form and extending entirely around the interior of the frame. Slidably mounted within

2

the frame 9 is a closure panel 10 adapted for slideable movement in a vertical plane within the channel frame 9. The upper edge of the panel is provided with any approved type of handle or hand grip 11 for convenience in raising or lowering the panel into any desired position to regulate the passage of air through the louvres and through the opening between the top of the front wall 5A and the top wall or sill 4.

10 In order that the panel 10 may resist the force of gravity and remain in any of its adjusted positions, I provide a balance in the form of a coil spring 12 mounted within a housing 13, carried by the side walls 2 and 3 of the frame 1. The outermost end of the spring may be attached to the upper edge of the panel 10 by any suitable means, or I may secure one end of a tape to the panel and its opposite and to the outermost end of the spring.

15 To prevent any leakage of air between the front wall 5A and the closure panel 10, I provide weather stripping 14 along the bottom edge of the panel and also as at 15 along the top edge of the front wall. The weather stripping 15 is always in wiping contact with the panel and that on the panel is in like contact with the inner surface of the front wall 5A. When the panel is moved into its uppermost position the two weather stripings engage with each other.

20 While I have shown a particular form of embodiment of my invention, I am aware that many minor changes therein will readily suggest themselves to others skilled in the art without departing from the spirit and scope of the invention. Having thus described the invention: what I claim as new and desire to protect by Letters Patent is:

25 A ventilator adapted to be installed in an opening in the wall of a building, said ventilator consisting of a frame having vertical side walls, a vertical partial front wall, a bottom wall and a top wall, a plurality of downwardly inclined horizontal louvers fixedly mounted within the frame in spaced relation to each other, a screen mounted within the frame between the louvers and said partial front wall, a second vertical partial front wall slidably mounted within the frame and adapted to close the opening between the top of said first mentioned partial front wall and the top of said frame, means carried by the frame and attached to said second partial wall for arresting its movement in any location between said opened and closed positions, said means comprising a pair of coil springs attached at one of their ends to said second partial front wall and at their opposite ends to said frame, a strip of weather

stripping of channel formation in cross section secured across the bottom end of said slideable partial front wall and having one of its sides in wiping contact with the inner surface of said first mentioned partial front wall, a companion strip of weather stripping secured across the top end of said first mentioned partial front wall and having one of its sides in wiping contact with the outer surface of said slideable partial front wall, and both of said strips of weather stripping being adapted for engagement with each other when said slideable partial front wall is moved vertically into a closed position.
